UNITED STATES PATENT OFFICE

JOHN T. VOGEL, OF RICHMOND HILL, NEW YORK

DESIGN FOR A NAPKIN

Application filed January 13, 1931. Serial No. 38,298. Term of patent 3½ years.

To all whom it may concern:

Be it known that I, JOHN T. VOGEL, a citizen of the United States, residing at Richmond Hill, county of Queens, and State of New York, have invented a new, original, and ornamental Design for Napkins, of which the following description, in connection with the accompanying drawing, is a specification.

My design consists essentially of a central

figure including a single sign of the zodiac on a relatively large scale, surrounded by a border including this and other signs of the zodiac on a relatively small scale.

The figure is a plan view of a napkin, showing my new design.

I claim:

The ornamental design for a napkin, as shown and described.

JOHN T. VOGEL.
